Patented Dec. 16, 1924.

UNITED STATES PATENT OFFICE.

JOHN PERSON, OF MORA, MINNESOTA, ASSIGNOR OF ONE-HALF TO BROTHER SOLMON-
SON, OF MORA, MINNESOTA.

BAG HOLDER.

Application filed April 3, 1924. Serial No. 703,917.

To all whom it may concern:

Be it known that I, JOHN PERSON, a citizen of the United States, residing at Mora, in the county of Kanabec and State of Minnesota, have invented certain new and useful improvements in Bag Holders; and I do hereby declare the following to be a full, clear, and exact description of the invention, such as will enable others skilled in the art 10 to which it appertains to make and use the same.

This invention relates to a bag holder of the type adapted to hold fabric or other sacks so that the mouth of said sacks will 15 be held in open position to receive the desired contents.

It is an object of this invention to provide a simple and efficient structure of bag holder adapted to hold bags of various sizes, 20 both in circumference and length.

It is a further object of the invention to provide such a bag holder comprising oppositely disposed curved arms adapted to hold the bag, which arms are resiliently 25 held in position and adjustable vertically on a standard secured to a suitable base.

It is also an object of the invention to provide such a bag holding means having a plate disposed thereon adapted to be positioned at the rear of the bag mouth to direct 30 material thereinto, which plate, preferably, is adjustable as to size.

These and other objects and advantages of the invention will be fully set forth in the 35 following description made in connection with the accompanying drawings in which like reference characters refer to the same parts throughout the different views, and in which,

Fig. 1 is a view in side elevation of the device showing a bag in dotted lines in position thereon;

Fig. 2 is a horizontal section taken on the line 2—2 of Fig. 1, as indicated by the arrows, shown on an enlarged scale;

Fig. 3 is a partial view in rear elevation of the standard used;

Fig. 4 is a view in rear elevation of the adjustable plate used;

Fig. 5 is a view in side elevation as seen from the right of Fig. 4;

Fig. 6 is a top plan view of the device,

certain portions being shown in dotted lines in different positions;

Fig. 7 is a vertical section taken on the line 7—7 of Fig. 6; and

Fig. 8 is a vertical section taken on the line 8—8 of Fig. 6, both as indicated by the arrows; Figs. 3 to 7 being shown on a larger scale than Fig. 1.

Referring to the drawings, the device comprises a base 1 which may be made of various forms but which is shown as comprising spaced members 1^a between which extend the boards 1^b secured thereto to form a platform. The bracket 2 is secured adjacent the rear edge of the base 1 substantially centrally thereof by screws or other suitable means, and a standard 3 is bolted to the brackets 2 and rises vertically therefrom. While the standard 3 will be made in various forms, in the embodiment of the invention illustrated, the same is shown as of channel shape with the side flanges of the channel projecting rearwardly. The sides 75 of said channel are formed with upwardly directed ratchet teeth 3^a spaced throughout the upper part of the standard. A cross bar or cross head 4 is provided which may be of any suitable desired shape but which, in the embodiment of the invention illustrated, is also shown as of channel shape, the horizontal flanges of the channel projecting forwardly. Said channels are provided with an opening centrally thereof adapted to receive the channel or standard 3 so that the crosshead is vertically slideable on said standard. The member 4 has a pair of ears 4^a 80 projecting rearwardly from its web between which is pivoted a lug projecting forwardly 90 from the curved pawl 5, said pawl having an upwardly extending portion 5^a forming a handle and being normally pressed to engaging position with one of the teeth 3^a by a compression coiled spring 6 fitting over 95 a projection on said pawl and a short projection on the rear of member 4. It will thus be seen that the pawl 5 holds the crosshead 4 in various vertical positions. The standard 3 is also provided with a plurality of spaced holes 3^b disposed centrally of its web which are adapted to receive stop members which may take the form of cotter pins 100 7 disposed above and below the member 4

and forming stops therefor. Adjacent each end of the member 4, headed pivot pins 8 extend through the flanges thereof and form the pivots for hubs 9^a of a pair of levers 5 having their forward portions formed as curved flat members 9. The members 9 are oppositely disposed with their concave sides facing each other and are carried at their rear ends by downwardly projecting portions 9^b depending from hubs 9^a. The hubs 9^a also have rearwardly projecting arms 9^c extending therefrom which have their rear ends apertured and connected by a tension coiled spring 10 extending between said 10 arms and connected in said apertures. The hooks or bands 9 have upwardly projecting hooks 9^d on their rear sides and spaced thereon, three of said hooks being illustrated on each arm. The terminals of the arms 9 are 15 provided with eyelets and a small handle 11 is adapted to be pivoted to the end of either arm, said handle having a knob at its outer end and a stop lug 11^a at its inner end. The cross head 4 has a plurality of holes 12 therein at each side in any one of which the respective pivots 8 may be disposed so that the hubs 9^a will be disposed in different positions, thus positioning the arms 9 for 20 different sized bags. The arms 9^c are stopped 25 in their movement toward each other by stop pins 13, there being one pin for each arm, and said pins being adapted to be disposed in any one of a plurality of holes 14 formed in parallel ribs 4^b projecting from 30 the rear of the web of member 4, there being 35 one of said ribs adjacent each end of said member. A frame 4^c of substantially triangular shape projects rearwardly and centrally from the rear of the web of cross head 4 and said frame has a rib 4^d extending centrally thereof at right angles to the length 40 of the cross head 4, which rib is disposed in a vertical plane and provided with a pair of slots 4^e. The spring 10 is adapted to be 45 pressed into said slots, the edges of said slots formed by the rib 4^b entering between the convolutions of said spring, as shown in Fig. 6. Disposed in front of the cross head 4 and the inner ends of arms 9 is a plate formed 50 of sections 15 and 16, the sections 16 having inturned flanges 16^a at its top and bottom adjacent one end forming a guideway in which plate 15 slides. The sections 15 and 16 each have secured thereto by rivets 55 or other suitable means, downwardly extending hooks 17, which hooks are adapted to be received in one of a plurality of holes 18 formed in the flanges of cross head 4. The cross head 4 has tongues 4^f projecting forwardly from and centrally from the flanges thereof to form a backing for the central part of the plates 15 and 16.

In operation, the bag to be filled will be passed in the rear of the plates 15 and 17 60 around the rear of one of the arms 9 and

hooked over the supporting hooks 9^d thereon. The other side of the bag will now be passed around the outside of the other arm 9. In order to easily place the bag on the latter arm 9 without undue strain, the handle 11 is grasped and the arm 9 swung inwardly against the tension of spring 10. There will now be sufficient slack in the bag 70 for the same easily to be passed around the outside of the arms and placed on the supporting hooks 9^d. With the bag so placed, the arm is released and the mouth of the bag is then held in wide open position, the front side thereof extending between the outer ends of arms 9. The handle 11 75 preferably is made detachable so that it can be easily connected to the end of either arm 9 to suit the convenience of a left-handed or right-handed operator. It will be understood that the pivots 8, in their hubs 9^a will be disposed in proper holes 12 to suit the size of the bag to be filled and that the hooks 17 carrying plate sections 15 and 16 will be correspondingly adjusted. After the bag is positioned on the arms 9, cross head 4 and 80 said arms will be adjusted on standard 3 by manipulation of the pawl 5 so that the bottom of the bag just rests on the base 1, as shown in Fig. 1. Grain, or other material 85 can now be easily and quickly placed in the bag, the plate formed by sections 15 and 16 at the rear of the bag acting to direct the grain thereinto. The arms 9 are tensioned 90 by the spring 10 so that the bag is continuously held in tensioned and open position. If the hubs 9^a are moved inwardly, as indicated in dotted lines in Fig. 6, the spring 10 will be disposed in the inner slot 4^e, as indicated in dotted lines in Fig. 6, so that 95 the proper tension will be had upon the arms 100 9^a. The tension of the arms 9 and 9^c can be adjusted by disposing the pin 13 in either one of the holes 14. It will be noted that 105 the ratchet teeth 3^a are directed upwardly so that the crosshead 4 and the parts carried thereby can be raised by merely being lifted or moved upwardly on standard 3, the same being held from downward movement by 110 the pawl 5. The provision of the stop members 7 eliminates the possibility of jerking the cross head entirely off the standard or of releasing the same to drop too far. When 115 the bag has been filled the cross head can be quickly dropped to be out of the way during the bag tying operation. The cross head will simply drop to the lower cotter pins 7. The upper pins 7 will be set so that when the cross head is again raised it will be in proper position for the next sack. The pins 7 can, of course, be set to suit different lengths of sacks. When the cross-head is lifted it may be necessary to hold 120 the platform 1 with the foot. By supporting the sack so it just reaches the platform the same will fill properly at the corners and 125 130

a shaking or lifting of the sack will be unnecessary. The holder is also out of the way during the filling operation. The pins 13 prevent undue tension in the bag when 5 it is engaged by arms 9. The triangular frame 4^c adds rigidity and strength to the structure as well as forming a support for the rib 4^f.

From the above description it is seen that 10 applicant has provided a simple and efficient structure of bag holder and one that can be easily and quickly operated. The parts of the device are comparatively few and when assembled, the device has no tendency 15 to become disarranged. The device has been amply demonstrated in actual practice and found to be very successful and efficient.

It will, of course, be understood that various changes may be made in the form, 20 details, arrangement and proportions of the parts without departing from the scope of applicant's invention, which, generally stated, consists in the novel parts and combinations of parts disclosed and defined in the 25 appended claims.

What is claimed is:

1. A bag holding device comprising a standard, oppositely disposed curved arms projecting therefrom disposed substantially 30 in a horizontal plane with their concave sides toward each other, said arms being oscillatable about vertical pivots, resilient means normally tending to swing said arms apart, a cross head carrying said pivots having two series of holes therethrough, a pivot 35 for each arm being insertible in different holes of one series whereby the spacing of said arms may be varied to suit different sized bags, and adjustable stops in said cross head limiting the outward movement of said 40 arms.

2. A bag holding device comprising a standard, a cross head secured to and extending at each side of said standard adjacent its upper end, levers pivoted in the 45 ends of said cross head about vertical axes and having rearwardly projecting arms, a coiled tension spring connecting said arms, said levers having oppositely curved arms 50 projecting to the front of said cross head and having their concave sides toward each other, said cross head having means for mounting said levers in different positions, and means for holding said spring in flexed 55 position in certain positions of said levers.

3. A bag holding device comprising a standard, oppositely curved arms projecting forwardly therefrom disposed substantially in a horizontal plane with their concave 60 sides towards each other, said arms being oscillatable about vertical pivots, resilient means normally tending to swing said arms apart, said pivots and arms being adjustable toward and from each other, and a material 65 directing plate disposed in front of said

standard and the inner ends of said arms and extending between the latter, said plate being adjustable as to length in accordance with the adjustment of said pivots and arms.

4. A bag holding device comprising a 70 standard, a cross head adapted to slide vertically thereon and be held in different positions thereon, levers adjustably pivoted in said cross head at each side of said standard about vertical axes having rearwardly projecting arms and having curved bag holding arms carried at their forward ends and disposed in front of said standard, a spring connecting said rearwardly projecting arms, said cross head having a rearwardly projecting portion having spaced upwardly opening slots therein, said spring being adapted to be disposed in said slots in flexed position in certain positions of said levers.

5. A bag holding device comprising a 75 standard, a cross head vertically slidable thereon, means for holding said cross head in different positions on said standard, a bag holding means carried on said cross head, and stops on said standard above and below 80 said cross head limiting its upward and downward movement, said stops being arranged to be disposed in different vertical positions.

6. A bag holding device comprising a 85 base, a standard rising therefrom, a cross head comprising a channel member having its flanges projecting forwardly and horizontally, said flanges having alined apertures therethrough receiving said standard, 90 pivot pins extending through said flanges at each side of and equidistant therefrom, levers having intermediate hubs journaled on said pivots and disposed between said flanges, said levers having arms projecting 95 through openings in the web of said cross head, a tensile spring connecting said arms, stop means for limiting the movement of said arms under the influence of said spring, and said levers having downwardly turned portions forwardly of said hubs from which extend forwardly flat curved arms having their concave sides facing each other, said 100 curved arms carrying bag supporting hooks.

7. The structure set forth in claim 6, said 105 standard being formed of a channel bar having its flanges projecting rearwardly and formed with ratchet teeth, a pawl pivoted to the rear of said cross head adapted to co-act with said teeth, said standard 110 having a plurality of spaced holes through the web thereof, and means disposed in said holes above and below said cross head to limit the movement thereof.

8. The structure set forth in claim 6, said 115 cross head having a triangular frame projecting from the rear thereof carrying an upstanding rib having slots therein in which said tensile spring is disposed and may be held in various positions.

9. The structure set forth in claim 6, said stop means comprising pins and said cross head having rearwardly projecting horizontal plates on its rear side having a plurality of spaced holes therethrough, in any one of which said pins may be disposed.

10. A bag holding device comprising a base, a standard rising therefrom, a cross head vertically slidable on and adapted to be held on said standard, oppositely curved bag holding arms secured to said cross head and projecting forwardly therefrom and a plate carried by said cross head and disposed in front of said cross head and the inner ends of said arms and projecting above the latter.

11. The structure set forth in claim 10, said arms being adjustable toward and from each other and said plate comprising laterally telescoping sections, and means for

supporting the same in various positions whereby its width can be varied to suit the adjustment of said arms.

12. A bag holding device comprising a standard having upwardly directed ratchet teeth thereon, a crosshead vertically slidable on said standard, a handle lever pivoted to said crosshead and constituting a pawl engaging said ratchet teeth to hold said crosshead in various positions, bag holding means carried by said crosshead, and adjustable stops in said standard above and below said crosshead to limit the movement of said crosshead whereby when a bag is filled said handle lever may be operated to permit said crosshead to drop to said lower stop and slacken the top of the bag so that the same may be tied.

In testimony whereof I affix my signature.
JOHN PERSON.
